UNITED STATES PATENT OFFICE

ERNEST FLAGG, OF NEW YORK, N. Y.

COMPARTMENT VEHICLE

Application filed July 25, 1930. Serial No. 470,749.

This invention relates generally to the construction of compartment vehicles and while not necessarily limited thereto, refers more particularly to an improved construction of a railway sleeping car.

The discomforts and disadvantages of the ordinary twelve section type of sleeping car having upper and lower berths with one stateroom are common knowledge and, while the recently developed compartment car having individual rooms will eliminate the discomforts of the above mentioned type, the number of persons accommodated by the latter has been materially reduced. In the latter type the rooms are of such unnecessary height that approximately one-third of the cubic content of the car is wasted, which might be utilized to good advantage.

It is, therefore, the outstanding object of the present invention to provide an improved sleeping car or vehicle construction by virtue of which a maximum number of separate rooms or compartments are provided in the allotted space, which rooms or compartments are of a size which afford greater comfort and freedom to the occupant, such as providing standing space alongside the berth with sufficient head-room for a person of not unusual height.

It is a further aim of the present invention to provide in a railway sleeping car permanent berths which may be made up before the car is occupied or started and in which the compartments are of a sufficient size to accommodate, in addition to each berth, a chair, which may be shifted about to suit the occupant, as well as being provided with individual wash-basins and toilet hoppers.

The invention furthermore comprehends in a railway compartment car, an arrangement of upper and lower compartments to which access may be as readily gained to the upper as to the lower compartments whereby the adversity to and consequent loss of fares from failure to occupy the upper berths is eliminated.

Other objects of the invention reside in the comparative simplicity of construction of the car or vehicle, the economy with which the

same may be built and operated, and the general efficiency derived therefrom.

With the above recited and other objects in view, reference is had to the following specification and accompanying drawings in which there is exhibited one example or embodiment of the invention, while the claims define the actual scope thereof.

In the drawings:

Figure 1 is a fragmentary sectional plan view taken approximately on the line indicated at 1—1 of Figure 3.

Figure 2 is a similar view taken approximately on the line indicated at 2—2 of Figure 3.

Figure 3 is an enlarged transverse sectional view taken approximately on the line indicated at 3—3 of Figure 1.

Figure 4 is a similar view taken approximately on the line indicated at 4—4 of Figure 1.

Figure 5 is a fragmentary longitudinal sectional view taken approximately on the line indicated at 5—5 of Figure 1.

Referring to the drawings by characters of reference, the car body includes side walls 10 and 11 which are of slightly lesser height than that of an ordinary car, while the side walls 12 and 13 of the clear story roof portion are of slightly greater height than ordinarily while the combined overall height of the car remains standard.

A longitudinal partition 14 corresponding approximately to the height of the side walls 10 and 11 and adjacent one side wall 11 defines together therewith a corridor C which extends throughout the length of the car. Vertical longitudinally spaced partitions 15 extend in the lower part of the car from the longitudinal partition 14 to the opposite side wall 10 while the upper portions of said partitions 15 extend completely between the side walls 12 and 13 of the clear story roof structure. Each of the subdivisions defined by the partitions 15 is again vertically subdivided by fore and aft stepped partitions 16 including an upper stepped portion 17, a lower stepped portion 18 and a riser portion 19. In practice the upper stepped portion 17 will be spaced from the floor 20 of the car approxi-

mately seven feet while the lower stepped portion 18 will be spaced from the ceiling 21 approximately the same distance to afford between said portions the proper head room for an average person to stand erect with sufficient clearance.

In the upper compartments U the berths B will be supported directly upon the upper surface of the upper stepped portion of the partition 16, while in the lower compartments L, the berths B will be arranged to underlie the lower stepped portion of the horizontal portions. An inclined wall or partition 22 extends upwardly from the foot or inner end of the berths of the lower compartments L and steps 23 project outwardly therefrom by virtue of which access may be gained to the upper compartments U. Doorways D in the longitudinal partition 14 lead from the corridor C to the lower compartments L, while doorways E are provided in the longitudinal partition sections F at the head of the stairway formed by the steps 23 to gain access to the upper compartments U. Between the free side of the berths of both the upper and lower compartments and the transverse partitions 15 space is afforded for a chair 24 which may be freely moved about to suit the convenience of the occupant of the compartment. In the lower compartments L, the toilet hoppers 25 swivelly move from a normally out-of-the-way position under the berths to an exposed useable position as clearly illustrated in dotted and full lines in Figure 1 of the drawings. In the lower compartments L, the wash-basins 26 may be mounted to swing from a normally vertical inactive position to a horizontal useable position.

In the upper compartments U, the toilet hoppers 27 and wash-basins 28 are swiveled for movement from a normally inactive out-of-the-way position underlying the lower portion of the clear story roof structure to an exposed active position as clearly illustrated in dotted and full lines in the drawings.

Between the end walls 29 of the car and the endmost partitions 15, a vestibule V is provided which may be subdivided by a partition 30 to afford a porter's closet W for the storage of towels and bed clothing and other accessories.

From the foregoing it will thus be seen that within the space of a standard sleeping car, a sufficient number of compartments have been afforded for the accommodation of approximately as many persons as can be accommodated by the present type of twelve section sleeping car in which each compartment provides for both the privacy and comfort of the occupant. It will also be apparent that permanent berths permit of the making up of the beds prior to the start of the car or its occupancy. Due to the staggered arrange-

ment of the berths of each pair of upper and lower compartments provision is made in each compartment for standing space alongside the berth having sufficient head-room to allow the occupant to stand erect while dressing and undressing, washing, or for other purposes. In order to avoid increasing the standard height of the car, it will be observed that the floor of the standing space of each upper compartment is at a lower plane or level than the ceiling of the standing space of the lower compartment and that said floor overlies and serves as a ceiling for the berth of the lower compartment. Conversely, the standing space alongside the berth of the lower compartment directly underlies the berth of each upper compartment.

While there has been illustrated certain details of construction, it is to be clearly understood that no limitation is necessarily intended thereto and that variations and modifications which properly fall within the scope of the appended claims may be resorted to when desired.

I claim:

1. In a sleeping car or the like, a longitudinal corridor at one side thereof, a row of pairs of superposed transversely arranged compartments respectively communicating with the corridor, said compartments each having a berth and standing space alongside the berth, the berth of the upper compartment of each pair being arranged over the ceiling of the standing space of the lower compartment and the floor of the standing space of each upper compartment being arranged over the berth of the lower compartment and disposed below the plane of the ceiling of the standing space of the lower compartment, said upper and lower compartments each having a doorway establishing communication between the corridor and the standing space of the compartments and a stairway leading from the corridor to the doorway of each upper compartment, said stairway consisting of an inclined inner end wall at the berth portion of each lower compartment and outwardly projecting steps from said inclined wall.

2. A compartment vehicle including lower side walls and upper side walls offset inwardly with respect to the lower side walls, transverse partitions longitudinally subdividing the vehicle and fore and aft stepped horizontal partitions in each of said subdivisions defining together therewith a row of lower and upper compartments, and a longitudinal corridor adjacent one of the lower side walls having communication respectively with the upper and lower compartments.

3. A compartment vehicle including lower side walls and upper side walls offset inwardly with respect to the lower side walls, transverse partitions longitudinally subdividing the vehicle and fore and aft stepped

horizontal partitions in each of said subdivisions defining together therewith a row of lower and upper compartments, a berth in each compartment extending transversely of the vehicle and having a standing space alongside thereof, the upper surface of the lower stepped portion of each of the horizontal partitions providing floors for the standing space of the upper compartments and the lower surface of the upper stepped portion thereof providing ceilings for the standing space of the lower compartments.

4. A compartment vehicle having relatively narrow and wide upper and lower portions a longitudinal partition adjacent one side wall of the lower portion thereof defining together with said side wall, a corridor extending throughout the length of the vehicle, longitudinally spaced transverse partitions extending from the longitudinal partition to the opposite side wall of the lower portion and extending from the floor to the ceiling of the vehicle and completely across the upper narrow portion and subdividing said vehicle longitudinally and fore and aft stepped horizontal partitions in each of said subdivisions defining together therewith a row of pairs of upper and lower compartments.

5. A compartment vehicle having relatively narrow and wide upper and lower portions a longitudinal partition adjacent one side wall of the lower portion thereof defining together with said side wall, a corridor extending throughout the length of the vehicle, longitudinally spaced transverse partitions extending from the longitudinal partition to the opposite side wall of the lower portion and extending from the floor to the ceiling of the vehicle and completely across the upper narrow portion and subdividing said vehicle longitudinally and fore and aft stepped horizontal partitions in each of said subdivisions defining together therewith a row of pairs of upper and lower compartments, a berth in each of said compartments having standing space alongside thereof, the upper surface of the lower stepped portion of each of the horizontal partitions providing floors for the upper compartments and the lower surface of the upper stepped portion thereof providing ceilings for the standing space of the lower compartments.

6. A compartment vehicle having relatively narrow and wide upper and lower portions a longitudinal partition adjacent one side wall of the lower portion thereof defining together with said side wall a corridor extending throughout the length of the vehicle, longitudinally spaced transverse partitions extending from the longitudinal partition to the opposite side wall of the lower portion and extending from the floor to the ceiling of the vehicle and completely across the upper

narrow portion and subdividing said vehicle longitudinally and fore and aft stepped horizontal partitions in each of said subdivisions defining together therewith a row of pairs of upper and lower compartments, a berth in each of said compartments having standing space alongside thereof, the upper surface of the lower stepped portion of each of the horizontal partitions providing floors for the upper compartments and the lower surface of the upper stepped portion thereof providing ceilings for the standing space of the lower compartments, the berths of each of the lower compartments underlying the lower stepped portions of the horizontal partitions, and extending through the longitudinal partition to the opposite side wall of the lower portion.

7. A compartment vehicle having relatively narrow and wide upper and lower portions, a longitudinal partition adjacent one side wall of the lower portion thereof defining together with said side wall, a corridor extending throughout the length of the vehicle, longitudinally spaced transverse partitions extending from the longitudinal partition to the opposite side wall of the lower portion and extending from the floor to the ceiling of the vehicle and completely across the upper narrow portion and subdividing said vehicle longitudinally and fore and aft stepped horizontal partitions in each of said subdivisions defining together therewith a row of pairs of upper and lower compartments, a berth in each of said compartments having standing space alongside thereof, the upper surface of the lower stepped portion of each of the horizontal partitions providing floors for the upper compartments and the lower surface of the upper stepped portion thereof providing ceilings for the standing space of the lower compartments, the berths of each of the lower compartments underlying the lower stepped portions of the horizontal partitions and the berths of the upper compartments directly overlying the upper stepped portions thereof, and extending completely across the width of the upper narrow portion of the vehicle.

8. A compartment vehicle having relatively narrow and wide upper and lower portions, a longitudinal partition adjacent one side wall of the lower portion thereof defining together with said side wall a corridor extending throughout the length of the vehicle, longitudinally spaced transverse partitions extending from the longitudinal partition to the opposite side wall of the lower portion and extending from the floor to the ceiling of the vehicle and completely across the upper narrow portion and subdividing said vehicle longitudinally and fore and aft stepped horizontal partitions in each of said subdivisions defining together therewith a row of pairs of upper and lower compartments.

ments, a berth in each of said compartments having standing space alongside thereof, the upper surface of the lower stepped portion of each of the horizontal partitions providing floors for the upper compartments and the lower surface of the upper stepped portion thereof providing ceilings for the standing space of the lower compartments, the berths of each of the lower compartments underlying the lower stepped portions of the horizontal partitions and the berths of the upper compartments directly overlying the upper stepped portions thereof and extending completely across the width of the upper narrow portion of the vehicle and partially overlying the longitudinal corridor.

9. A railway car of standard length, height and width including an upper portion of a reduced width, a corridor extending throughout the length of the car at one side of the lower portion thereof, transverse partitions subdividing the remainder of the car space longitudinally, stepped horizontal partitions in each of said sub-divisions defining upper and lower compartments, a berth in each compartment having a standing space alongside thereof, the upper surface of the lower stepped portion of each horizontal partition providing a floor for the standing space of the upper compartment, and the lower surface of the upper stepped portion thereof providing a ceiling for the standing space of the lower compartment, stairways leading laterally upwardly from the corridor to the floors of the upper compartment, and extending partially over the berth space of the corresponding lower compartment.

Signed at New York, N. Y., in the county of New York and State of New York, this

40 22nd day of July, A. D. 1930.
